UNITED STATES PATENT OFFICE

2,538,462

MINNOW BUCKET

William Klatt, Saco, Mont.

Application November 17, 1947, Serial No. 786,390

3 Claims. (Cl. 43—56)

1

This invention relates to new and useful improvements in buckets and the primary object of the present invention is to provide a minnow bucket so designed as to permit a supply of air to enter the same for retaining the minnow therein in a live condition.

Another important object of the present invention is to provide a minnow bucket including a minnow receiving container and novel and improved means for supplying air to the receptacle.

A further object of the present invention is to provide a minnow bucket that is extremely small and compact in structure that will retain a large number of minnows in a live condition for a long period of time.

A still further aim of the present invention is to provide a minnow bucket of the aforementioned character that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present minnow bucket;

Figure 2 is a longitudinal vertical sectional view taken substantially through the center of Figure 1;

Figure 3 is a transverse horizontal sectional view taken substantially on the plane of section line 3—3 of Figure 1, and;

Figure 4 is an enlarged fragmentary vertical sectional view of the upper portion of the present minnow bucket, and showing the means for supplying air to the air chamber provided between the inner and outer walls of the outer container.

Referring now to the drawings in detail, wherein for the purpose of illustration, there is disclosed a preferred embodiment of the present invention, the numeral 10 represents a substantially cylindrical outer container generally, comprising an annular outer wall 12, a bottom wall 14, an annular upper wall portion 16 at the upper edge of the outer wall 12, and an inner annular wall 18 integrally formed with the wall portion 16. The inner wall 18 is spaced relative to the outer wall 12 to provide an air chamber 20, and the lower edge 22 of the inner wall 18 terminates adjacent the bottom wall 14 to provide an air passage 24.

2

Projecting outwardly through a suitable aperture provided in the wall portion 16, is an externally threaded air nipple 26 that is normally retained in a closed position by an internally threaded closure cap 28.

Positioned within the outer container 10, is an inner container 30, the outer periphery of which is loosely embraced by the inner wall 18 to provide a further air chamber 32. The upper edge of this inner container 30 is turned outwardly to provide an annular bearing flange 34 that frictionally bears upon the wall portion 16. This flange 34 is provided with a slot or opening 36 that loosely engages the closure cap 28 whereby the inner container may be removed from the outer container without restrictions.

Hinged to the flange 34, as at 38, is a perforated, annular closure plate 40, the edges of which normally bear upon the flange 34. This closure plate 40 is provided with a suitable hand grip 42 facilitating the removal of the inner container from within the outer container.

In order to retain the closure plate 40 in a normally closed position, there is provided a lug 44 projecting outwardly from the flange 34 that lockably engages a notch 46 provided in the free end of a pivotal latch 48 mounted on the closure plate. This lug is provided with an enlarged head or shouldered portion 50 that prevents disengagement of the latch with the lug as the inner container is removed from the outer container.

To facilitate the carrying of the entire minnow bucket, including the inner and outer container, there is provided a pivotal carrying bail 52 carried by the outer wall 12 of the outer container.

It should be noted, that the inner container is provided with air perforations 54 that communicate with chambers 20 and 32.

In practical use of the present invention, the outer cylindrical container 10 is filled partially with water and the cap 28 is applied to the nipple 26. The inner container 30 is then inserted into the outer container 10 and water is forced into the chamber 20. The level of the water in the chamber 20 is below the level of the water in the inner container 30 since air in the upper portion of the chamber 20 is compressed as the column of water rises in the chamber 20.

Water in the chamber 20 is available to the fish in the inner container 30, also, as the water in the inner container 30 is forced into the chamber 20, upon tilting of the entire device, a certain amount of air in the upper end of the chamber 20 will tend to be forced through the

perforations 54 and into the inner container 30, thereby increasing the volume of water in the chamber 20 and reducing the volume of air in the chamber 20.

In order to replace the volume of air in the chamber 20 it is necessary to lift the pail 30, and since a vacuum is present in the upper end of the chamber 20, the vacuum must be relieved by removal of the cap 28.

The cap 28 is again applied to the nipple 26 and the inner container 30 lowered into the outer container with the column of liquid in the chamber 20 below the column of liquid in the inner container 30.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention what is claimed as new is:

1. A minnow bucket comprising an outer container having spaced inner and outer walls defining an air chamber, an upper wall joining said inner and outer walls and having an air vent for said chamber, a closure controlling said air vent, an inner container having openings therein communicating with said air chamber, closure means for said inner container and means for locking said last-mentioned closure in a closed position to said upper wall, said inner container having a flanged portion supported on the upper wall of said outer container.

2. A minnow bucket comprising an outer container having inner and outer spaced walls and an upper wall joining the inner and outer walls, an inner container positioned in said outer container and having a flange portion bearing against the upper wall of said outer container, an outlet nipple carried by the upper wall of said outer container for supplying air to said outer container, a closure cap for said nipple, a hinged closure for said inner container, and means for locking said closure in a closed position to said upper wall, said flange portion having a slot receiving the nipple.

3. A minnow bucket comprising an outer bucket including an outer wall, a bottom wall and an inner wall spaced relative to said outer wall, an upper wall connecting the upper edges of said inner and outer walls, an inner container embraced by said inner wall, said inner and outer walls defining an air chamber, said inner container having openings communicating with said air chamber, a nipple carried by said upper wall for supplying air to said chamber, a perforated closure for said inner container, and means for locking said closure in a closed position, said inner container having a flanged portion resting upon the upper wall of said outer container, said flanged portion having a peripheral slot receiving said nipple.
